CONVEYER FOR MANIPULATING CYLINDRICAL ARTICLES

Alonzo B. Bradley, Nyack, N. Y., assignor to The Fibre Conduit Company, Orangeburg, N. Y., a corporation of New York

Application November 16, 1932
Serial No. 642,849

11 Claims. (Cl. 198—127)

This invention relates to a type of conveyer primarily intended for the handling of cylindrical articles, for example fibre ducts, in drying ovens, and the improvement herein described has especially 5 advantages when used in that connection, but is also susceptible of a wider application.

The type of conveyer and the method of handling cylindrical bodies thereon, to which this improvement relates, are set forth in an application 10 for U. S. Patent of John P. Keller, Serial No. 530,709, filed April 16, 1931.

The conveyer shown in this Keller application comprises a series of rolls mounted in a substantially horizontal plane with their axes fixed as 15 to movement of translation both with relation to each other and to their support. The rolls are all driven at the same speed in clockwise direction, so that the upper sides of the rolls present a series of surfaces all moving from the feed 20 or front end of the conveyer toward the rear or discharge end.

The cylindrical bodies to be manipulated by the conveyer under the Keller method,—for example the moist fibre ducts taken from the forming 25 machine and placed upon a conveyer of this type arranged in a drying oven,—are placed by successive feeding actions in the bights between the successive spaced rolls. The relative sizes of the rolls and cylindrical bodies and the spacing 30 of the roll axes are such that the cylindrical bodies will lie in the bights between the rolls out of contact with each other and will be in free axial rotation in the drying oven until a movement of translation is imparted to carry them forward, 35 each body moving from one bight to the next. In practice, the successive impulses of translation are initiated by imparting to the rearmost body on the train of rolls, a thrust in the direction 40 of feed through a new body fed to the conveyer, so that the drying period of the cylindrical bodies is determined by the period of intermission between the feeding in of new bodies and by the length of the train of rolls in the drying oven.

The present improvement relates to improved 45 means for feeding cylindrical bodies to the conveyer and initiating the movements of translation of the bodies over the train of rolls.

As herein illustrated and described, the invention is applied to five superposed conveyers 50 which may be simultaneously or selectively charged if desired, according to whether all or only certain of them are supplied with bodies to be treated. Thus the output of the drier as a 55 whole may be regulated in accordance with the

supply of raw articles from the forming machine, which supply may vary with demand.

In carrying out my invention, as applied to handling fibre ducts directly from the forming machine, the raw ducts are supplied at a loading 60 or supply station to a transfer chain, the operation of which, (initiated when successive ducts are placed upon the chain), charges the advance rolls of the conveyer train or trains with ducts to be dried, and intermittently imparts feeding 65 movements to such ducts, in cooperation with the tractive effect of the rolls upon the ducts, to give movements of translation of the ducts through successive steps of their progress over the train of rolls from the charging to the dis- 70 charging end of the oven, the ducts being given, in the intermissions of their movements of translation, free axial rotation, by reason of their tractive engagement with the conveyer rolls.

The movements of translation are initiated in 75 the present invention, by an improved pusher feeding mechanism cooperating with the conveyer rolls and adapted to engage one of a plurality of cylindrical bodies in the bights of the rolls and impart a broadside advancing movement to said 80 bodies over said rolls from bight to bight. The pusher member proper has a U-shaped body faced with a flexible contacting material which avoids injury to the moist raw bodies introduced upon the roll conveyer in the dryer. 85

The feeding mechanism of the present invention comprises means for supplying, at predetermined intervals, ducts or the like to the bight between the first two rolls of a train of rolls, or to a number of such trains, if more than one be 90 used; means for imparting to the duct or ducts so supplied, a motion in the direction of feed so as to initiate a movement of translation of all of the ducts on the conveyers; and means operated when ducts are successively placed upon the 95 chain for initiating these movements, together with other details of mechanism and methods of operation, all of which will be described in the following specification, reference being made to the claims for the novel combinations and methods involved. 100

In the accompanying drawings, which illustrate the invention by way of example,

Figure 1 is a horizontal sectional view of the machine at the feed end of the conveyer, only 105 a part of the train of rolls being shown and the entire delivery or discharge end of the machine being cut away. The figure also shows the machine broken away on a longitudinal central line to indicate that the actual proportionate width 110

of the machine is greater than that here shown; Figure 2 is a vertical sectional view of the same end of the machine exhibited in Figure 1, taken on the line 2—2 of Figure 1, and looking in the 5 direction of the arrows. The pusher mechanism is shown in retracted position;

Figure 3 is a side view of the same end of the machine with part of a side frame for the transfer mechanism broken away adjacent the loading station. The pusher actuating mechanism is 10 shown in the position it occupies when the pusher mechanism is in the retracted position shown in Figure 2;

Figures 4, 5 and 6 are detail vertical sectional 15 views of the feed end of the conveyer train illustrating successive positions of a pusher arm as it moves from the position shown in Figure 2;

Figure 7 is a detail vertical sectional elevation 20 illustrating the method of discharging a duct from the transfer chain;

Figures 8, 9 and 10 are detail sectional views 25 illustrating three successive positions of a duct upon the runway leading to the conveyer rolls after discharge from the transfer chain;

Figure 11 is a fragmentary side view of the 30 ascending and descending runs of the transfer chain showing means for locking and releasing the cradle;

Figures 12 to 16 show diagrammatically in elevation, five positions of the transfer chain;

Figure 17 is an elevation of transfer chain and 35 adjacent parts, showing ducts in position;

Figure 18 is a diagram of the circuits of the operating motors;

Figure 18a is a detail view illustrating modified 40 arrangement of the starting switch; and

Figure 19 is a diagrammatic table illustrating 45 the succession of operations.

An important application of the invention being 50 to conveyers for drying ovens for fibre ducts, I have indicated at 6 part of the oven wall within which are mounted one or more duct-conveyers. 6a, 6a are side frames for the transfer mechanism. Five decks of conveyers are here shown 55 marked respectively I, II, III, IV, V. Each conveyer comprises a substantially horizontal train of rolls 7 of equal diameter and equally spaced apart, having their shafts or trunnions 8 rotatably mounted in fixed bearings supported, as by 60 brackets 9, from a rigid frame 10 within the oven. The shafts project at one side, here shown as the right-hand side, beyond the oven where each carries a sprocket wheel 11 splined or otherwise rigidly attached to the shaft or axis of the roll.

Each series of sprocket wheels 11 is engaged 65 by the upper run of a continuous chain 12, driven from any suitable source of power, not shown, adapted to keep the rolls in continual rotation in clockwise direction while the machine is in 70 operation. The return runs of the several chains are shown at 13. The oven is suitably heated, as by steam pipes 14.

The cylindrical articles, as for example ducts 75 15, to be handled by the conveyer, rest in the bights between successive rolls, where they are given free axial rotation during the drying operation by reason of the tractive engagement of their surfaces with the smooth cylindrical surfaces of the rolls. By describing the rolls as 80 having smooth cylindrical surfaces, I intend to indicate that they have such a substantially uninterrupted surface as to afford support from end to end to ducts placed upon them and to exert tractive effect on said ducts due to surface 85 friction only. When in this position, there is no

tendency for the ducts to have a movement of translation over the train of rolls, the tractive effect of the two rolls in the bight between which each duct rests being balanced and resulting in a rotation of the duct in situ.

In order to initiate a movement of translation of the ducts over the train of rolls, an outside agency is required and for this purpose pushing members 16 are provided. These comprise flattened U-shaped members 17 carried by arms 18 80 fixed to a transverse shaft 19 as by set screws 20 so as to be adjustable to proper position and in alignment upon said shaft. A suitable number of these pusher members, for example five, may be spaced along the shaft. Two are shown in Figure 1, the intermediate three being omitted by reason of the breaking away of the conveyer along its central line. The shaft 19 is supported by end 85 bearings 22 and intermediate bearings 23 on the frame of the machine. A strip or web 24, of fabric, such as felt, is stretched across the open side of the trough or U-shaped members 17 and fastened at the edges thereof to provide a contacting surface of the pushers with the ducts of a flexible nature which will contact with a considerable surface of the duct when the pusher is brought in contact with it, and yield sufficiently to prevent injury to the duct, which, at the time of its placing in the oven, is relatively soft and liable to be marred by any rough handling.

Each shaft 19 is provided at one end with an arm 25, Figure 3, adjustably secured to the shaft as by set screw 26, and carrying an adjustable weight 27, and immediately within the arm 25 there is adjustably attached to each shaft, as by 100 set screw 28, a forked arm 29 having cam follower rolls 30 resting upon a cam plate 31 fixed to vertically moving rod 32 guided in vertical bearings 33 fastened to the frame of the machine. The rod 32 is connected by connecting rod 34 to the 105 outer end of pitman 35 fulcrumed at 36 to a standard 37 arising from the frame of the machine, and the pitman 35 is actuated by a piston 38 of a thruster 39 of well-known construction, the electrical connection of which is such that 110 when the motor of the thruster is energized, piston 38 rises, lifting the rod 34 and the arms 25, 29 until the pushers 16 assume the retracted position shown in Figure 2, and the de-energizing of the motor allows the rod 32 to drop, leaving 115 the arms 25, 29 free to fall under the action of gravity exerted upon the weights 27 so that the pushers pass successively from the position shown in Figure 2, through those shown in Figures 4, 5 and 6. The weights 27 are varied or adjusted 120 according to the weight of the cylindrical object being handled.

In the Keller method of handling ducts as carried out in the present machine, it is intended 125 that the duct, which is to be progressed through the oven, shall be placed in position in the bight between the first two rolls 7 of the train before the movement of translation over the train of rolls is initiated, or if there be more than one train, then that a duct shall be in such position 130 in the bight between the first two rolls of each train in use before such movement of translation is initiated, and that in the latter case, such movements shall all be initiated simultaneously. In order to so charge the conveyers, especially 135 where a number of trains of rolls are employed, I employ a transfer mechanism which will now be described, but which in the specific form shown is not a part of my invention and for which other forms of transfer mechanism may be substituted. 140

40, 40 are endless sprocket chains mounted on the side frames 6a, one at each side of the machine, comprising side links 41 and sprocket pins or rollers 42 engaging upper and lower sprocket 5 wheels 43 driven (by intermediate connections, not shown), from the motor 44 (Figure 18) so that the outer run of the chains will pass upward close to the loading platform 45 and the inner run thereof will descend in close proximity to the several decks near the outer edges of a series 10 of inclined runways 46, one for each deck, each terminating at its lower edge close to the upper surface of the first roll of one of the trains of rolls 7. The loading platform 45 is preferably 15 slightly trough-shaped to receive and retain a duct placed thereon, and is mounted on the front of the machine at a convenient height for the operator. A series of duct supporting trough-shaped cradles 47 are mounted upon the chains 20 and extend approximately the width of the machine as shown in Figure 1. These cradles (see especially Figure 7) are carried by bracket arms 48 keyed to transverse shafts 49 which are journalled at their ends in guide blocks 50 sliding in 25 vertical guide grooves 51, 51a in the side frames 6a of the machine. The guide blocks are pivoted at their upper ends on studs 52 upon side links of the transfer chains 40 and are caused to retain an upright position while the cradles are 30 being transferred in the open space above the guide grooves, by pendant weight beams 53 hung loosely from shafts 49. A lock arm 54 is pinned near one end of each shaft 49 and has a gate 55, see Figure 11 especially, engaged by a detent pin 35 56 on a detent arm 57 pivoted at 58 to guide block 50. The engagement of pin 56 in gate 55 is assured by spring 59. Upon the free end of the detent arm 57 is a follower roll 60. During the 40 upward movement of the guide block 50 in the guide groove 51, the roll 60 lies in front of and out of contact with the side web 61 of the guide groove, and the lock arm 54 is maintained in the upright position shown at the left of Figure 45 11. The descending guide groove 51a is extended on one side by the cam plate 62 with which the follower roll 60 engages when the guide block 50 is in the guide groove 51a, so that the detent arm 57 is lifted as shown at the right hand of Figure 50 11, raising the detent 56 from the gate 55 leaving the lock arm 54 free to move to the dotted 55 position shown, when the guide block 50 and the loaded cradle carried thereby have reached a position at which the duct carried by said cradle should be discharged upon the runway 46, appropriate to that cradle.

There are five duct carriers, (comprising each a cradle 47 and the members for supporting it on the chain), equally spaced along the length of the loading chain and numbered 1, 2, 3, 4 and 5. 60 The shaft 49 of each cradle has rigidly attached to it a yoke or bracket 63 carrying two follower rollers 64, 65. The yokes 63 are arranged at such points on the shafts that roller 65 will engage one or other of the cam rails 1a, 2a, 3a, 4a, 65 5a, on cam plates 62a, 62b, each of which rails has a cam-shaped notch 66 in the horizontal plane of one or the other of the decks I to V into which the roller 65 may drop when a duct is to be discharged at that deck. The rollers 64 run in contact with the guide plates 62, 62c, which have cam projections 67 arranged opposite the cam notches 66, and in a vertical plane removed from those of rollers 64, as shown in Figure 1, for initiating the tilting motion of the cradle. I have shown 70 three of the cam rails 1a, 5a and 3a on cam plate 75 62a on one side of the machine and the remaining two, 2a and 4a, on the cam plate 62b on the other side of the machine, and the cooperating cams 67 are disposed also on opposite sides of the machine to correspond with the several cam rails and their notches 66.

It has been noted that there are five duct carriers on the transfer chain and five decks of conveyors. The chain is moved for each operation of the machine the distance between two of the cradles, but during two of these periods, the pusher mechanism is operated in one direction to initiate the motion of translation of the ducts across the train of rolls and in the other direction to restore the pusher arms to their normal position at rest, shown in Figure 2, in which position the runways 46 are unobstructed by the pushers to allow the charging of the first two rolls of each conveyer with fresh duct. Arrangement is made, therefore, to cause the charging 80 of the five conveyers with fresh ducts during three steps only of the motion of the transfer chains. To accomplish this, two cradles are caused to discharge during one step, two at the second step, one at the third step, and none at 85 the other two steps while the pusher is being actuated. The series of operations will be clear from an examination of Figures 12 to 16 and 19. Each cradle is charged by the operator with fresh duct at the loading station 45 as it reaches 90 the same. By reason of the mechanism already described, each cradle will discharge only at its appropriate deck, that is to say, cradle 1 at deck I, etc., as indicated at column 3 in the table, Figure 19. Figure 12 indicates the position of the 95 loading chain with cradle 3 at the supply station 45. In moving to bring cradle 3 to this point, the chain has carried cradle 5 past deck V and deposited a duct there. In the table, Figure 19, the condition at the several decks at this point is 100 shown in first column "3"—the clear circles indicating previously discharged ducts on decks I—IV, and the crossed circle indicating the just-discharged duct on deck V. At this moment therefore all decks are charged, that is to say, 105 a duct lies in the bight between the first two rolls of each train as illustrated in Figure 17. During the next two motions of the chain, indicated by columns 4 and 5 on Figure 19, the pushers are operated, the chain has moved 110 through the positions shown in Figures 13 and 14, and no cradle 1—5 has passed a correspondingly numbered deck I—V, and accordingly no ducts have been discharged from the loading chain. The cycle then begins again with cradle 1 approaching the supply station, as shown in Figure 15. In moving to this position, from that shown in Figure 14, cradles 1 and 2 pass their corresponding decks I and II and discharge their ducts, so that decks I and II have been supplied 115 with fresh ducts, as illustrated in column 1 by the crossed circles, and the remaining three decks have not been supplied. In making the next movement to the position shown in Figure 16, at which cradle 2 is at the supply station, cradles 3 120 and 4 have passed their decks III and IV, and discharged their loads, so that as shown in column 2, Figure 19, four decks are charged. At the next movement of the train, as shown in column 3, following column 2, the cradle 5 is unloaded 125 and all decks are charged ready for the next operation of the pusher mechanism.

Across the machine, approximately above the discharge end of each runway 46 (Figures 1, 7-10) is a slow-down device for the ducts running down 130

the runway, comprising preferably a wooden bar 68 forming an inertia member carried by a hanger or hangers 69 of flexible material, such as fabric, hung from brackets 70 fastened to a 5 cross-beam 71 of the machine frame.

In the electric circuit diagram, Figure 18, the motor 44 for operating the transfer chain 40 and the thruster 39 for operating the pushers 16 are shown connected to a source of electric current 10 at +-. The circuit from the line through the motor is normally interrupted at the arm F of a two-contact switch E, F. The circuit of manual switch A, in parallel to the motor, includes the solenoid 72 and normally closed switch B adapted 15 to be operated by any one of a series of pins B¹—B⁵ properly positioned upon the chain 40 to open the solenoid circuit at the right moment to stop the loading cradles successively at the loading station 45. The arm E of the two-contact 20 switch E, F is for maintaining the circuit closed when the manual switch A is released.

The circuit for operating the pusher members passes through the motor of thruster 39 and through the normally closed switch H of the two-contact switch G, H, and back to the line. A parallel circuit includes the switch D adapted to be momentarily closed by a pin D¹ on the chain 40. The operating pin D¹ is upon the chain slightly below the pin B³ so as to time the closing of 25 the switch D immediately after the switch B has been temporarily opened by the pin B³. In circuit with the switch D is a normally closed switch C, adapted to be opened by the pin C¹ attached to the chain 40 at a position following 30 that of pin D¹ that will allow the full forward swing of the pusher members before the pin C¹ opens the switch C. In circuit with the switch C is the solenoid 73. The arm G of the two-contact switch G, H is in a circuit around the switch 35 D to maintain the solenoid circuit when the switch D is open. The several switches B, C and D may, as indicated in Figure 1, be mounted in a common 40 plug 74 inserted in a suitable socket in the side frame 6a adjacent to the upward moving run of 45 one of the chains 40 which carries the switch operating pins B' etc., C', D'.

The operation is as follows: Figure 2 shows the transfer chain in position with carrier cradles 1 and 2 supplied with ducts to be treated and the 50 cradle 3 approaching the loading platform 45, on which rests a duct 15 ready for loading. At this time carrier cradles 4 and 5 are also empty, having just previously unloaded ducts at decks 4 and 5, and, as shown in Figure 2 and at column 3 of 55 Figure 19, all the decks stand charged with fresh ducts. The next two operations of the transfer chain, initiated by the depression of the manual switch A (for placing new duct upon the chain), will not discharge any more ducts on any of the 60 decks but will cause the forward and backward operations of the pushers, leaving them in the retracted position shown in Figure 2. When cradle 3 reaches the loading station, the operator manually supplies it with a fresh duct from the loading platform and again starts the chain. In the 65 form of mechanism shown, the starting is accomplished when the operator presses the manual switch A, which closes the circuit of solenoid 72 and thus closes the motor circuit which is held 70 closed by the switch E when the manual switch is released by the operator, and it remains closed until the chain has completed a movement and the next cradle 4 reaches the loading station 45, at 75 which point the switch B is opened by the pin B⁴ just long enough to allow the switch E, F to open,

stopping the motor. During this stage in the motion of the chain, as will be seen in Figure 13, none of the carrier cradles passes its corresponding conveyer deck and therefore no duct is discharged from the transfer chain. The starting of the chain to move cradle 3 upward from the loading station closes the switch D whose operating pin D¹ is, as will be seen on Figure 3, a short distance below the operating pin B³. The solenoid 73 opens the thruster motor circuit at H and closes the solenoid retaining circuit at G, and the cam rod 32 moves downward carrying the several cam plates 31 away from the follower rolls 30 of the weighted arms 29, and the pusher shafts 19 are rotated to bring the pushers 16 from the position shown in Figure 2 into contact with the several ducts resting upon the first two rolls of each train and carrying through the motion of the ducts illustrated in Figures 4, 5 and 6, which show the successive positions of the ducts on one train of rolls. The freshly supplied duct which lies in the bight between the first two rolls of the train is pressed upon by the pusher to move it away from tractive engagement with the first rolls of the train, the action of the pusher, cooperating with the lifting action of the second rolls of the train, raises such duct to bring it into contact with the duct which lies in the bight between the second and third rolls of the train. Thereupon a series of contacts take place between the 105 several ducts upon the conveyer as shown in Figures 4 and 5. The contacting surfaces of the ducts having a tendency, by reason of their tractive engagement with the successive rolls, to oppose each other's motion, are prevented from 110 relative rotation and scuffing, and the group of ducts move forward under the cooperating pressure of the pusher and rotation of the rolls until the pusher reaches the limit of its swinging motion, at which point the ducts settle into the several bights between the rolls, starting with the 115 second roll, and continue there in free axial rotation until the next succeeding motion of translation over the train of rolls is imparted to them after the first two rolls of the several trains have 120 again been charged with fresh ducts.

The gravity action of the weighted arms 25 is adjusted by proper choice and placing of the weights 27 so as to effect this feeding motion without injury to the ducts, and at such speed as 125 will complete the pushing motion, and also allow the retraction of the pushers while cradles 4 and 5 are being brought to the loading station by two successive actions of the switches A and B. The switch opening pin C¹ is, as shown in Figure 130 3, located at such point on the chain as to open the switch C when the pusher has completed its pushing motion to reach the position shown in Figure 6. The solenoid 73 is thereby deenergized, the two-contact switch G, H restored to the position shown in Figure 18, at which the thruster motor circuit is closed and the cam rod 32 is again elevated to its uppermost position, restoring the pushers 16 to the normal position shown in Figure 2, in which they are out of the way of 140 ducts being discharged from the loading chain to the runways leading to the several conveyers.

During these motions of the chain 40, as each cradle 47 reaches the loading station 45, it is supplied with fresh duct, and when the next cycle 145 of operations begins with cradle 1 moving from the position shown in Figure 14 to that shown in Figure 15, cradle 1 passes deck I and cradle 2 passes deck II, thus unloading ducts at these two decks, as shown at the column headed 1 in 150

Figure 19; in passing to the position shown in Figure 16, cradles 3 and 4 are unloaded at decks III and IV, and in passing to the position shown in Figure 12, cradle 5 is unloaded on deck V, and so on. It will be noted and is illustrated in the table, Figure 19, that hand-switch A and automatic stop switch B are operated for each step motion of the transfer chain, and that pusher control switches D and C are only operated when the cradles 4 and 5 are approaching the loading station.

The above description of operation refers to a condition in which all conveyers are kept fully charged and in which, therefore, all cradles receive a load as they pass the charging station. If only one or more of the conveyers,—owing to diminished supply from the forming machine, a supply governed by the demands of the business,—is to receive ducts, only the cradle or cradles appropriate to the selected conveyer or conveyers, will be supplied with duct at the charging station by the operator, the remaining conveyers running idle, or being disconnected from operation, as desired.

25. Other means than the hand-switch A may be used for the intermittent starting of the machine in operation when an empty cradle reaches the loading station and there receives a fresh duct to be transferred to the drier. It may for example be automatically operated by the placing of the duct on the transfer cradle. I have indicated diagrammatically, by way of example, in Figure 18a, such an arrangement wherein the circuits in general correspond to those shown in Figure

35. 18. Here the switch A', supported upon the machine frame, is operated by downward movement of the cradle 47a which has slight capacity for vertical movement, as by being hinged at one edge, and which engages the free arm of the switch at the other edge and is limited in its downward movement, by impingement upon a rigid part of its support upon the transfer chain.

I claim:—

1. In mechanism of the character described, 45 the combination of a train of rolls for manipulating cylindrical objects, supply mechanism including a travelling cradle for cylindrical objects, means for tripping the cradle to discharge a cylindrical object therefrom, means for transferring the cylindrical object to the train of rolls, and means for pushing the cylindrical object sidewise to impart to it a broadside movement of translation on the rolls.

2. In mechanism of the character described, 55 the combination of a train of rolls for manipulating cylindrical objects, means for supplying a cylindrical object to the train of rolls, and a pusher mechanism for imparting a movement of translation to a cylindrical object on the train of rolls, said mechanism comprising a pusher, a pusher retracting rod, actuating mechanism interposed between said rod and the pusher, and controlled means for reciprocating said rod to cause advancing and retracting of the pusher.

65. 3. In mechanism of the character described, the combination of a train of rolls for manipulating cylindrical objects, means for supplying a cylindrical object to the train of rolls, and a pusher mechanism for imparting a movement 70 of translation to a cylindrical object upon the train of rolls, said mechanism comprising a pusher, automatic means for causing the advance and retraction of said pusher, and controlled means for initiating the operation of said 75 automatic means.

4. In mechanism of the character described, the combination of a train of rolls for manipulating cylindrical objects, means for supplying a cylindrical object to the train of rolls, pushing mechanism for imparting a movement of translation to a cylindrical object upon the train of rolls, and means controlled by the supplying means to cause the operation of the pushing mechanism.

5. In mechanism of the character described, the combination of a train of rolls for manipulating cylindrical objects, means for supplying a cylindrical object to the train of rolls, controlled means for operating said supplying means, pushing mechanism for imparting a movement of translation to a cylindrical object upon the train of rolls, and means controlled by said supplying means to cause the operation of the pushing mechanism.

6. In mechanism of the character described, the combination of a train of rolls for manipulating cylindrical objects, means for supplying a cylindrical object to the train of rolls, an electric motor for operating the supplying means, pushing mechanism for imparting a movement of translation to a cylindrical object on said train of rolls, a second electric motor for operating said pushing mechanism, and electric circuits, one including a manual control for the supplying means operating motor and an automatic control thereof operated by the supply means, and the other including automatic control for the pusher mechanism operating motor operated by the supplying means.

7. In mechanism of the character described, 100 the combination of a train of rolls for manipulating cylindrical objects, means for supplying a cylindrical object to the train of rolls, and pushing mechanism for imparting a movement of translation to a cylindrical object on the train of rolls, said pushing mechanism comprising a pusher, means for positively retracting said pusher, and gravity operated means for advancing the pusher.

8. In mechanism of the character described, 110 the combination of a train of rolls for manipulating cylindrical objects, means for supplying a cylindrical object to the train of rolls, a pusher reciprocable to impart a movement of translation to a cylindrical object upon the train of rolls, a gravity operated arm connected to advance the pusher to cause such movement of translation, and a motor connected to cause the retraction of the pusher.

9. In mechanism of the character described, 120 the combination of a train of rolls for manipulating cylindrical objects, means for supplying a cylindrical object to the train of rolls, an oscillatory shaft, a pusher mounted on said shaft adapted to cause a movement of translation to 130 a cylindrical object on said train of rolls, a weighted arm upon said shaft to cause the advance of the pusher, a reciprocable rod having a cam, an arm on the oscillatory shaft engaging said cam to retract the pusher, and a motor for 140 positively operating the reciprocable rod to retract the pusher.

10. In mechanism of the character described, 145 the combination of a plurality of trains of rolls for manipulating cylindrical objects, a plurality of pusher mechanisms for imparting simultaneous movements of translation to cylindrical bodies on said trains of rolls, means for supplying cylindrical bodies to all of said trains of rolls, controlled means for operating said sup-

ply means in successive steps, means controlled by the motion of the supply means for discharging the cylindrical bodies to the several trains of rolls selectively during certain of the steps of movement of the supplying means, and means controlled by the movement of the supply means during the remaining steps to actuate the pusher mechanism.

11. In mechanism of the character described, the combination of a plurality of trains of rolls for manipulating cylindrical objects, the trains being arranged in vertical series, a plurality of pusher mechanisms for imparting movement of translation to cylindrical bodies on said trains of

rolls, a vertically arranged endless conveying mechanism adjacent to the receiving ends of the trains of rolls, and having means for carrying individual cylindrical objects, means for imparting successive movements to the endless conveying mechanism, means causing the discharge of cylindrical objects from said endless conveying mechanism during a portion of its movements, and means actuated during the remainder of such movements of the conveying mechanism for simultaneously operating all of said pusher mechanisms.
